HAIRCUTTER'S GUIDE

Louis T. Fox, Sr., Ottawa, Ill.

Application March 13, 1953, Serial No. 342,104

4 Claims. (Cl. 132—45)

This invention relates in general to barbing equipment and more specifically to a haircutter's guide.

At the present time there are used many types of hair trimming devices which if properly utilized permit one to cut their own hair or other's hair without conventional barbing equipment. These devices are being widely used inasmuch as their use permits the saving of the time generally expended in waiting in line to have one's hair cut and also in view of their economy. However, the hair trimming devices now on the market require a considerable amount of skill to properly trim one's hair and may be utilized only to remove excess hair. It is therefore the primary object of this invention to provide an improved haircutter's guide which may be utilized by an unskilled person for the purpose of cutting another's hair, said guide permitting an accurate cutting of one's hair to the desired style.

Another object of this invention is to provide an improved haircutter's guide which may be utilized in combination with scissors, clippers, or other barbing equipment for the purpose of an unskilled person giving another person a haircut, said guide being so designed whereby the barbing operation is, in fact, a complete haircut and is not limited to a simple trimming operation.

Another object of this invention is to provide an improved haircutter's guide which is adapted to fit on one's head in a manner similar to one's hat and which may be utilized to cut one's hair completely without any manipulation of the guide whatsoever.

A further object of this invention is to provide an improved haircutter's guide which may be of any desired style to permit one's hair to be cut to a style which he or she desires.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view of the haircutter's guide, which is the subject of this invention, and shows the same mounted on the person's head in the process of giving the person a haircut through the use of electric clippers, the clippers being shown in dotted lines;

Figure 2 is a top plan view of the haircutter's guide and shows the general outline of the same, the person's head being shown in dotted lines;

Figure 3 is a rear elevational view of the haircutter's guide of Figure 1 and shows the contours of the rear ribs which form the rear portion of the guide; and,

Figure 4 is a longitudinal vertical sectional view taken substantially upon the plane indicated by the section line 4—4 of Figure 2 and shows the contour of certain of the ribs.

Referring now to the drawings in detail, it will be seen that there is illustrated the haircutter's guide which is the subject of this invention, the guide being referred to in general by the reference numeral 10. The guide 10 is

2

intended to have an inner outline which conforms to the contour of one's head and an outer outline which conforms to the contours of a desired style haircut.

The haircutter's guide 10 includes a main, longitudinally extending rib 12 which is intended to extend from one's forehead to the nape of their neck. Carried by the main rib 12 and secured to the rear portion thereof adjacent the rear lower end is a secondary rib 14 which is generally U-shaped in outline. The rib 14 is generally angular in elevation and includes a downwardly and rearwardly sloping bight portion.

Referring now to Figure 2 in particular, it will be seen that extending between the main rib 12 and the secondary rib 14 at the front portion of the secondary rib is a plurality of transversely extending auxiliary ribs 16. The auxiliary ribs are arcuate in elevation and vary in length to conform to the desired outline of one's sideburns and one's ears. It will also be noted that the auxiliary ribs 16 have lower free ends of reduced depth as to give the sideburns a tapering effect.

Extending between and secured to the rearmost auxiliary rib 16 and the secondary rib 14 is a plurality of longitudinally extending auxiliary ribs 18 which are disposed on the opposite sides of the main rib 12 and are in spaced parallel relation therewith. The auxiliary ribs 18 are both arcuate in outline and are varying in length to produce the desired trim at the rear of one's head. Also, the lower free ends of the auxiliary ribs 18 are of a tapering depth to produce the desired effect at the back of one's head.

Disposed between the rearmost auxiliary ribs 16 and the outermost auxiliary ribs 18 are a plurality of radially extending auxiliary ribs 20. The auxiliary ribs 20 are secured at their upper ends to either of the rearmost auxiliary rib 16 or an associated outermost auxiliary rib 18 and have their lower portions connected to the secondary rib 14. It is to be understood that the auxiliary ribs 20 fill the space between the rearmost auxiliary ribs 16 and the outermost auxiliary ribs 18 to finish the contour of one's haircut.

Referring now to Figure 1 in particular, it will be seen that the lower ends of all of the auxiliary ribs 16, 18 and 20 extend below the secondary rib 14 to which they are secured. It will also be understood that each of the ribs forming the guide 10 is formed of a flexible material whereby the same may resiliently fit one's head so as to be retained thereon.

Referring now to Figure 1 in particular, it will be seen that the haircutter's guide 10 is mounted on a person's head which is referred to in general 22. The person's hair 24 is first combed to the desired style, the style being that for which the guide 10 is intended. Then the guide 10 is firmly positioned thereon so that the hair in excess of the desired haircut style will project beyond the individual ribs of the guide 10. Then by utilizing an electric clipper 26 or other barbing implements, such as scissors, and using the individual ribs of the guide 10 as guides, the excess hair may be cut from the person's head 22. After all of the excess hair has been trimmed through the use of the guide 10 the result is a neat and attractive haircut of the desired style which is the equivalent to a professional haircut.

It will be understood that the ends of the auxiliary ribs 16, 18 and 20, outline the contour of one's hair style and that the excess hair may be removed along the sideburns 26, the ear 28 and the back of one's neck 30 through the use of a razor (not shown). In this manner, not only is the hair trimmed to the desired contour, but also all excess hair from one's head is removed.

It is intended that the guide 10 be produced in many different styles and sizes and formed of relatively cheap material so that each individual may own a guide of the

desired style which will fit him. It will be understood that the hair guides 10 will be selected in the same manner as are hats at the present time. Inasmuch as each individual will have his own hair guide, it will be seen that the use of the hair guide will be a sanitary feature inasmuch as it cannot be utilized as a carrier of diseases from one person to the other, the guide being utilized by only one person.

While there has not been illustrated means for retaining the hair guide 10 on the person's head 22, it will be understood that inasmuch as the individual ribs of the guide 10 are flexible, it will be resiliently retained thereon due to the frictional gripping of the ribs. In case of a small child who has a tendency to attempt to shake off the guide 10, certain of the ribs, preferably the auxiliary 15 ribs 16, may be provided with a desired type of strap (not shown) which may pass under one's chin to retain the guide 10 thereon.

In view of the foregoing, it will be seen that there has been provided a novel and efficient guide for use in the 20 home cutting of one's hair, said guide being of an outline conforming to the desired style haircut. It will also be seen that the guide is so constructed and designed whereby the user of the same does not need any particular skill other than the ability to follow the guide. Therefore, 25 home haircuts may be given which will be undistinguishable from professional haircuts.

From the foregoing, the construction and operation of the device will be readily understood and further explanation is believed to be unnecessary. However, since 30 numerous modifications and changes will readily occur to those skilled in the art, it is not desired to limit the invention to the exact construction shown and described, and accordingly all suitable modifications and equivalents 35 may be resorted to, falling within the scope of the appended claims.

What is claimed as new is as follows:

1. A guide for use on the head of a person in hair-cutting operations comprising a frame fitting over the top, sides and back of the head and including a series of flat arcuate ribs spaced apart laterally and fitting edgewise transversely over the top and sides of the head with outer guiding edges for a haircutting tool and including a rearmost rib, means connecting said ribs together in spaced apart relation, and two series of flat longitudi- 45

nally curved and laterally spaced ribs extending downwardly from said rearmost rib and fitting edgewise against the head, said two series being spaced apart to fit opposite sides of the head at the back of the head and having outer guiding edges for said tool, the ribs in the two series lying in parallel planes oblique in each series with respect to those in the other series.

2. A guide according to claim 1, and a series of laterally spaced and longitudinally curved ribs extending downwardly from said rearmost rib and fitting edgewise over the back of the head between said two series with outer guiding edges for the haircutting tool.

3. A guide for use on the head of a person in haircutting operations comprising a frame fitting over the top, sides and back of the head and including a series of flat arcuate ribs spaced apart laterally and fitting edgewise transversely over the top and sides of the head and having outer guiding edges for a haircutting tool, and means connecting said ribs together in spaced apart relation, said series of ribs including a rearmost rib, and a series of laterally spaced and longitudinally curved ribs extending downwardly from said rearmost rib and fitting edgewise over the back of the head with outer guiding edges for the haircutting tool, the second named series of ribs being disposed in parallel planes at a right angle to said rearmost rib, and two series of flat longitudinally curved and laterally spaced ribs extending downwardly and fitting edgewise over the back of the head between said rearmost rib and the second named series of ribs, said two series having outer guiding edges for said implement and lying in planes oblique to the planes of said rearmost rib and said second named series of ribs.

4. A guide according to claim 3, said means comprising a U-shaped rib fitting forwardly over the head and attached to and spacing apart the ribs in the second named and said two series of ribs.
